UNITED STATES PATENT OFFICE.

ERNEST H. SCHRAGA, OF SALT LAKE CITY, UTAH, ASSIGNOR TO AUTOMATIC EXPLODER COMPANY, OF SALT LAKE CITY, UTAH.

SIGNAL APPARATUS.

1,277,138.

Specification of Letters Patent. Patented Aug. 27, 1918.

Application filed June 19, 1917. Serial No. 175,637.

To all whom it may concern:

Be it known that I, ERNEST H. SCHRAGA, a citizen of the United States, residing at Salt Lake City, in the county of Salt Lake 5 and State of Utah, have invented certain new and useful Improvements in Signal Apparatus, of which the following is a specification.

The present invention has to do with improvements in signal apparatus embodying an essential feature of its construction the exploder device which is disclosed in my co-pending application, filed December 27th, 1915, Serial No. 68,939, of which this 15 is a continuation in part.

The invention consists primarily of a suitable source of supply, preferably generative in character, of a gas or similar means which is introduced into a compartment or chamber 20 where it becomes explosive, as for example, with admixture with air, when subjected to ignition.

The following are among the numerous objects of my invention:

First, to produce an automatic, continuously operative signal of either an audible or visible nature, or both, useful in producing an alarm or warning and adapted for frightening wild animals from camps or 30 other places, as a guide to navigation, as a distress signal or such other adaptations as may be comprehended within the scope of its utility;

Second, to produce an apparatus in which 35 explosions will occur periodically at suitable intervals without the use of complicated mechanism or timing devices;

Third, to provide for the support of the device in such a manner as to take advantage 40 of the force of the explosions for the purpose of agitating a visible signal; also to effect displacement of the residue of the gas producing products; and,

Fourth, to provide for the rendering inoperative of the exploding function so as to enable the ignition means to be employed 45 as an illuminating apparatus.

Other objects and advantages of the invention will be apparent during the course 50 of the following description.

In the accompanying drawings, forming a part of this specification and in which like reference characters are employed to designate like parts throughout the same,

55 Figure 1 is a side elevation of an appara-

tus constructed in accordance with this invention,

Fig. 2 is a similar view looking at the device from a slightly different angle,

Fig. 3 is a vertical sectional view taken 60 about on the plane indicated by the line 3—3 of Fig. 2,

Fig. 4 is a horizontal sectional view on the line 4—4 of Fig. 2,

Fig. 5 is a detail sectional view on the 65 line 5—5 of Fig. 6, and,

Fig. 6 is a sectional view on the line 6—6 of Fig. 4.

Referring to the drawings, and specifically describing this invention, it will be 70 noted that the apparatus consists of the following main elements; the generator A, the exploder device B, the ignition means C, and a flag signal D, each of which will now be more specifically set forth,

The generator A is of a conventional type, by means of which a suitable gas is produced, and this member constitutes the source of supply of gas for the exploder device B. As is customary, the generator comprises the water compartment 1 from which the contents drop through the basket support 2 containing carbid, designated 3^a, under the control of the valve 4^a. Beneath the basket 2 is a suitable chamber 5^a to receive 75 the tailings or the residue from the carbid as the generation of the gas takes place.

The gas from the generator A passes to the exploder device B by way of the conduit 6^a, which as will be observed in Fig. 3, 80 includes a nozzle or burner 7 feeding the gas into the lower portion of the explosion chamber 8 of the exploder device. This conduit 6^a is suitably provided with an air intake 9, opening adjacent to the nozzle 7 and the 85 flow of the gas from this nozzle acts as an injector to draw a proper supply of air through the intake 9 into the explosion chamber for admixture with the gas to produce an explosive mixture. At one side and 90 at the lower portion of the chamber 8 is provided an opening 10, which is normally closed by a gate or closure member 11, pivotally mounted for gravitational action in a manner to be more clearly described as this 95 proceeds. Surrounding the inlet of the conduit 6^a and the tip of the nozzle 7 is a short nipple or pipe 12, the latter being removably disposed in its position projecting a substantial distance into the explosion chamber 100

110

2

8. It will be apparent that the gas flowing into the chamber will pass through this pipe to the upper portion of the chamber from which it is allowed to feed very gradually through a discharge outlet or bleed passage 13. This bleed passage coöperates with the ignition means C and extends through an opening 14 in the side wall of a hood or housing 15, surrounding the ignition member or burner 16 and having a glass front to render the light visible. The passage is formed with a shield 17 which prevents the gas escaping about the opening 14 and said passage, furthermore, is provided with a relatively small outlet 18 directing the gas discharged from the explosion chamber into the pocket 19 in the side wall of the hood 15, as shown most clearly in Fig. 6. This pocket surrounds the upper portion of the opening 14 and is so constructed as to retain therein a suitable supply of the gas, but is also provided with an escape outlet 20, permitting a certain amount of the gas to pass into the atmosphere. The function of this pocket is very important in that it effectively controls the flow of the gas with relation to the ignition means. In other words, it prevents the gas from passing from the chamber 8 into the hood 15 and there accumulating until it becomes of a sufficient quantity and of proper explosive characteristics to be subject to explosion, the result of which would be disastrous to the ignition means. The pocket retaining a small supply of the gas exposes this supply to ignition by the burner when the gas is of a proper quality to be fired, but permits a slight escape into the atmosphere through the outlet 20 until such explosive condition is present. The burner 16 receives its supply of gas from the generator A through the conduit 21, and this gas, of course, is supplied under natural pressure, such as is produced by a generator of this type. No pilot-lighting of the gas takes place by virtue of the said pocket.

The operation of the invention as hereinbefore described will be clear. The gas generation A having been started by the regulation of the water feed valve, the gas passes into the explosion chamber and likewise to the burner 16, which is lighted and allowed to remain burning. As a sufficient quantity of the gas and air is received in the chamber, and the feed thereof to the ignition means through the conduit 13 takes place, the gas is touched-off, and an explosion takes place in said chamber, the pressure of which is relieved by the automatic opening of the gate 11. Immediately the gate falls back to its normal position and the gas is again fed into the explosion chamber, the action being continuous, so that there will be a periodic explosion continuously operative so long as the generation of the gas is carried on. As has been said in referring to the pocket 19,

the gas at the opening 18 is prevented from igniting or pilot-lighting, and the same function is performed by the nipple or pipe 12, which surrounds the nozzle 7. This protective element 12 referred to, is important because it prevents the exploder device from becoming inoperative, and of course, the primary function of the apparatus would be defeated by any such action. The member 12, however, is subject to displacement at will so that the gas flowing into the chamber at the nozzle 7 may be lighted, and this will render the exploder inoperative while the apparatus still remains useful as an illuminating device or lantern *per se* inasmuch as the burner 16 would afford a suitable light.

The exploder device B is detachably connected to the generator A and to a suitable hanger 22, a winged nut 23 being employed at the upper portion of the chamber 8, for this purpose. The apparatus is primarily designed to be suspended by a spring 24, and a suitable number of rings 25. The purpose of this spring suspension will now be described. Each time an explosion takes place, as referred to above, the apparatus is accordingly jarred and such action will cause the device to vibrate upon its support, and obviously the light or ignition element C will have imparted to it motion so as to make more effective its signaling function. Therefore, not only do we have an audible signal as is afforded by the intermittent or periodic explosion, but also a visible signal as is provided by the constantly burning light, the sounds of the explosions attracting attention to the light.

In addition to this type of visible signal, I preferably attach to the supporting means, the flag-like signal D, and this also is caused to be waved incident to the explosions taking place in the explosion chamber 8. It may, therefore, be stated that the apparatus as a unit performs a triple function, that of a sound signal, secondly, a light signal, and lastly, a waving visible signal.

It will be apparent from this summary of its operation that the device will very readily carry out the objects initially set forth in this description, but I do not wish to be confined to the particular purposes herein mentioned, having in view the latitude of utility of such an apparatus.

It may be further stated that the arrangement of the hood 15 for the ignition means is also purposeful, as this member acts as a weather-vane, so that the apparatus is maintained with the light in an "out-of-the-wind" position by the action of the breezes upon the particularly shaped hood. It prevents any likelihood of the light being blown out by the wind, and rendering the apparatus inoperative, and in addition the constant swinging of the device with the wind tends to disclose the signal in all directions and

makes the functions of the device more effective.

Having thus described the invention, what I claim as new is:

- 5 1. In apparatus of the class described, the combination with a visible signal and support therefor, of means automatically operable periodically to produce movement of the signal on its support. 70
- 10 2. In apparatus of the class described, the combination with a light signal and support therefor, of explosion means mounted thereon, operable intermittently to produce an audible signal, said light being caused to move on its support by operation of the explosion means. 75
- 15 3. In apparatus of the class described, the combination with a flag-like signal and support therefor, of agitating means operable automatically at intervals to produce agitation of the signal aforesaid. 80
- 20 4. In apparatus of the class described, the combination with a flag-like signal and support therefor, of a sound producing signal carried by the support, the operation of the sound signal producing the signal operation of the flag signal. 85
- 25 5. In apparatus of the class described, the combination of a flag-like signal and support therefor, of a sound producing signal, and means for operating said sound signal to thereby produce movement of the flag-like signal on its support as a result of the sounding of the sound signal. 90
- 30 35 6. In apparatus of the class described, the combination with a flag-like signal and support therefor, of a sound producing signal comprising an explosion device, and ignition means coöperating with the latter for periodically causing the explosion, said flag-like signal being agitated as a result of the effect of the explosion. 95
- 40 7. In apparatus of the class described, the combination with a flag-like signal, a sound producing signal and a light signal, of a support common to said signals, said flag and light signals being operable on said support as a result of the effect of the operation of the sound signal. 100
- 45 50 8. In apparatus of the class described, the combination with a flag-like signal, a sound producing signal and a light signal, of a swinging support for said signals permitting their free agitative movement, said signals being agitated as a result of the operation of one of said signals. 105
- 55 9. In a device of the class described, the combination with a signal including a visible signal and explosion means operable periodically, of spring suspension means for said signal permitting free up-and-down movement of the signal, and oscillatory movement about its point of suspension as a result of the effect of the explosion. 115
- 60 65 10. In a device of the class described, the

combination with a visible signal, of a support therefor permitting movement of the signal on its support, and protective means for said signal for causing the same to assume an out-of-the-wind position. 120

11. In a device of the class described, the combination with a signal comprising a light, a swinging support therefor, and protective means surrounding the light and disposed to be affected by the wind to cause the light to move automatically to an out-of-the-wind position. 125

12. In a device of the class described, the combination with a signal comprising a light and a source of fuel supply therefor, of a protective hood arranged about the light, and supporting means permitting movement of the signal, said hood constituting a weather vane for maintaining the light in an out-of-the-wind position. 130

13. In a device of the class described, the combination with a signal comprising a continuously burning light, of an explosion chamber associated therewith, means for supplying an explosive medium to said chamber, supporting means for said signal, and means for maintaining the signal in a position protecting the light from the wind. 135

14. In a device of the class described, the combination with a signal, a source of fuel supply for said signal comprising a container for holding the fuel, and suspension means for said signal, of means for agitating the signal to cause the residue from the fuel to be displaced during operation of the signal. 140

15. In a device of the class described, the combination of a signal, a source of fuel supply for said signal comprising a gas generator, an exploder device communicating with the generator to receive its explosive medium, and yieldable suspension means for said generator adapted to be agitated incident to explosion in the exploder to thereby dislodge the tailings of the fuel in the generator. 145

16. In a signal device, the combination of a gas accumulating chamber having a discharge passage, ignition means adjacent to said passage, and means intermediate the passage and the ignition means for controlling the discharge and ignition of the gas. 150

17. In a signal device, the combination of a gas accumulating chamber having a discharge outlet constituting a touch-hole, ignition means contiguous to said touch-hole, and means coöperating with the latter to prevent pilot-lighting of said gas at the touch-hole. 155

18. In a signal device, the combination of a gas accumulating chamber, ignition means adjacent to said chamber, a protective hood for said ignition means, a gas feeding passage intermediate the chamber and the hood, and means coöperating with the outlet of 160

said feeding passage for receiving a portion of the flow of the gas and thus preventing accumulation of the gas in the hood.

19. In a signal device, the combination of 5 a gas accumulating chamber having a discharge passage, ignition means adjacent to said passage, and a pocket surrounding the discharge outlet whereby to control the feeding of the gas and the ignition thereof.

10 20. In a signal device, the combination of a gas accumulating chamber, ignition means adjacent to said chamber, a protective hood for said ignition means, a gas feeding passage intermediate the chamber and the hood, 15 and a pocket surrounding the outlet of the feeding passage to protect against pilot-lighting of the gas at the outlet and accumulation of the gas in the hood.

21. In a signal device, the combination of 20 an explosion chamber having a discharge outlet, a source of supply of gas for said chamber, a burner arranged adjacent to the outlet, and a protecting covering for said burner having an opening therein to receive 25 the gas from said outlet, said covering having a pocket at said opening for preventing the flow of gas into the covering while exposing the gas for ignition by the burner.

22. In a signal device, the combination of 30 an explosion chamber adapted to receive an explosive mixture, a discharge passage therefor, a burner adjacent to said passage, and a housing for said burner having an opening located at the outlet of said passage, the wall of said housing at the opening having a pocket therein, said pocket having an escape outlet, the explosive mix- 35

ture in said chamber being retained in said pocket and exposed to the ignition by the burner when the mixture has become explosive in character. 40

23. In a device of the class described, the combination of an explosion chamber, a source of supply of gas therefor including an inlet, ignition means for firing the accumulated charge in said chamber, and means surrounding the gas inlet for preventing pilot-lighting at said inlet. 45

24. In a device of the class described, the combination of an explosion chamber, a 50 source of supply of gas therefor including an inlet, ignition means for firing the accumulated charge, and a tubular member arranged at the inlet and projecting into the chamber so as to discharge the gas in the 55 chamber at a point remote from the inlet aforesaid, said tubular member preventing pilot-lighting of the gas at said inlet.

25. In a device of the class described, the combination of an explosion chamber adapted 60 to receive a supply of explosive mixture, a burner arranged exteriorly of the chamber, said chamber having a bleed passage adjacent to the said burner, a gas nozzle entering said chamber, and means coöperating 65 with the nozzle normally preventing pilot-lighting of the explosive mixture at the nozzle, said means being removable to permit the explosive mixture to be lighted at the nozzle whereby to render the explosive action inoperative. 70

In testimony whereof I affix my signature.

ERNEST H. SCHRAGA.
